UNITED STATES PATENT OFFICE.

JAMES H. TAYLOR, OF OWENSBORO, KENTUCKY.

DENTAL SURGICAL INSTRUMENT.

1,405,354.

Specification of Letters Patent. Patented Jan. 31, 1922.

Application filed February 24, 1921. Serial No. 447,389.

To all whom it may concern:

Be it known that I, JAMES H. TAYLOR, a citizen of the United States, residing at Owensboro, in the county of Daviess and 5 State of Kentucky, have invented certain new and useful Improvements in Dental Surgical Instruments, of which the following is a specification.

This invention relates to dental surgical instruments and more particularly to an instrument designed for use in the operation of cutting away the bony process in which a malederupted molar has become embedded, and the general object of the invention is to 10 provide an instrument which may be conveniently and effectually employed for cutting away a growth of the bony process over one side of an impacted inferior molar at either side of the mouth.

Another object of the invention is to provide an instrument which may be conveniently manipulated without liability of injury to the patient and which will operate 15 to smoothly cleave or cut away the portion 20 of the bony process of the inferior maxillary which has grown over the side of the malederupted molar and by the use of which instrument this portion of the bony process may by a single operation be cut away and 25 removed leaving a smooth surface which 30 will quickly heal.

In the accompanying drawings:

Figure 1 is a top plan view of one of the instruments embodying the invention, the 35 view illustrating the manner in which the instrument is to be employed in cutting away the bony process embedding the outer side of the lower left third molar;

Figure 2 is a similar view illustrating the 40 instrument which is to be employed at the right hand side of the mouth for a like purpose;

Figure 3 is a side elevation of the instrument shown in Figure 1;

Figure 4 is a front end elevation of the instrument, a portion of the jaws being shown in section.

The instruments shown in Figures 1 and 2 of the drawings are structurally identical, 50 the only difference being that one is adapted for use at the left hand side of the mouth and the other at the right hand side of the mouth, and therefore the specific description which is to follow will apply equally well 55 to both instruments.

The instrument in either case comprises a

pair of members one indicated by the numeral 1 and the other by the numeral 2, which members are disposed in crossed relation at their forward portions and connected by means of a pivot screw 3, the members 1 and 2 being provided with handle portions 4 and 5 respectively which may be knurled and suitably shaped to provide for most convenient manipulation of the instrument.

Forwardly beyond the pivot 3, the member 1 is provided laterally as indicated by the numeral 6, and thence downwardly and laterally inwardly to provide a blade which 70 is indicated in general by the numeral 7. The outer side of this blade is transversely and longitudinally curved and smooth throughout, as indicated by the numeral 8, whereas the inwardly presented side of the 75 blade is transversely and longitudinally cupped or concaved, as indicated by the numeral 9, so as to provide an approximately elliptical cutting edge 10 extending continuously along the end and side edges of 80 the blade 7.

The member 2 forwardly beyond the pivot 3 is extended outwardly laterally, as at 11, and thence downwardly and laterally inwardly to provide a gripping jaw indicated 85 by the numeral 12, this jaw having a concave inwardly presented face 13 which faces a concavity 9 of the blade 7. However, the concave face of the blade is presented inwardly and upwardly at an angle and the 90 gripping face of the jaw is presented downwardly and inwardly at an angle and the jaw 12 is considerably shorter than the blade 7. Likewise the blade is offset forwardly with relation to the jaw 12 as best illustrated in Figures 1, 2 and 3 of the drawings. The reason for this relative arrangement of the blades will be made apparent from the description of the use of the instrument which 95 is to follow.

By reference to Figure 1, which figure illustrates the manner of using one of the instruments, it will be observed that the molar A is malederupted and that as a result of the malederupture a portion B of the inferior maxillary C has grown over the outer side of the molar, this being the lower left third molar. In order to permit of this embedded molar being lifted from its impression in the inferior maxillary, it is necessary that the portion B of the bony process be cut away and this is accomplished by 105 110

the uses of the instrument shown in Figure 1, the instrument shown in Figure 2 being employed where a similar condition exists in the lower right third molar. In the use of the instrument the same is so disposed that the concave face 13 of the jaw 12 will be brought to bear against the inner side of the molar A immediately above the process, the jaws of the instrument straddling the molar and the blade 7, by reason of its greater length extending downwardly beside the process which has overgrown the outer side of the molar. Pressure is then brought to bear against the handle member 1 whereupon the blade 7 will be swung or closed in the direction of the jaw 12 and its cutting edge will be caused to cut through or cleave the bony process which embeds the outer side of the said molar. By reference to Figure 4 of the drawings it will be observed that the face of the jaw 12 engaged the tooth immediately above the process or in other words engages against one side of the crown of the tooth whereas the cutting portion of the blade 7 projects downwardly below the jaw to such a distance that its lower extremity is located at a point just above the lower end of the root of the molar tooth so that when the handle members of the instrument are closed, the cutting edge of the blade will cleave through the overgrown process. Other conditions being normal, the combined action of the blade 7 and jaw 12 upon the tooth will tend to tilt the tooth and partly dislodge the same.

If the bony process has grown about the inner side of the molar instead of about the outer side thereof, the instrument may be employed in a reverse manner or in other words the instrument which is employed in Figure 1 at the left side of the mouth would

under these conditions be employed at the right side of the mouth, and the instrument shown in Figure 2 would be employed at the left side of the mouth taking the place of the instrument illustrated in Figure 1.

Rearwardly of the pivot 3 the members 1 and 2 are provided with shoulder 14 which coact to limit the pivotal movement of the members to bring the blades toward the jaw.

While the instrument is described above as intended primarily for use in cutting the process in which a lower third molar has become impacted, it will be understood that it may be employed in the precise form illustrated or with slight modification, in releasing all other inferior teeth which may be molarupted or impacted, or malformed.

Having thus described the invention, what is claimed as new is:

1. A dental surgical instrument comprising a pair of pivoted members, a jaw carried by one of the members to engage one side of a tooth crown, and a blade carried by the other member and extending opposite the said jaw and of greater length than the jaw and having its outer portion provided with a cutting edge, the said blade being offset forwardly with relation to the jaw. 70

2. A dental surgical instrument comprising a pair of pivoted members, a jaw carried by one of the members to engage one side of a tooth crown, and a blade carried by the other member and extending opposite the said jaw and of greater length than the jaw and having its outer portion provided with a cutting edge, the jaw having its engaging faces presented laterally inwardly and downwardly, and the blade having its cutting portion presented laterally inwardly and upwardly. 80

In testimony whereof I affix my signature.
JAMES H. TAYLOR. [L.S.]
